UNITED STATES PATENT OFFICE.

WILLIAM F. COOK, OF PITTSBURGH, PENNSYLVANIA.

SHOE-TONGUE HOLDER.

Application filed September 18, 1922. Serial No. 588,940.

To all whom it may concern:

Be it known that WILLIAM F. COOK, a citizen of the United States, residing at Pittsburgh, in the county of Allegheny and

5 State of Pennsylvania, has invented new and useful Improvements in Shoe-Tongue Holders, of which the following is a specification.

This invention relates to holding devices 10 and has more particular relation to devices for holding the tongue of a shoe centered and preventing it from moving to an extreme position toward either side of the shoe, or working downward and wrinkling, 15 whereby undue wrinkling of the shoe across the vamp will be prevented and the shoe and tongue will present a neat appearance.

Another object of the invention is the provision of a device of the above character, 20 which contains all of the above and other advantages and in addition, is simple and economical in construction and which will not retard or interfere with the ready lacing of the shoe.

25 With the above and other objects in view, the invention further includes the following novel features and details of construction, to be hereinafter more fully described, illustrated in the accompanying drawings and 30 pointed out in the appended claim.

In the drawings:—

Figure 1 is a fragmentary front elevation of a portion of a shoe showing the invention in use.

35 Figure 2 is an enlarged sectional view on the line 2—2 of Figure 1.

Figure 3 is a detail perspective view of the invention per se.

Figure 4 is a view similar to Figure 1 40 showing a modified form of the invention.

Figure 5 is a sectional view on the line 5—5 of Figure 4.

Referring in detail to the drawings, and more especially to Figures 1, 2 and 3 of the 45 drawings, the reference character 10 indicates the side edges of the front opening of a laced shoe, the lacing of which is indicated at 11 and the tongue at 12.

Frequently the tongue of the laced shoe 50 becomes disarranged, that is it works to one side, with a result that the stocking is subjected to undue wear and the foot of the wearer frequently becomes calloused and sore. In addition, sometimes the tongue 55 will work downward with a result that the vamp of the shoe will become unduly creased,

so that in order to provide an effective device, the holder must hold the tongue against both sidewise and longitudinal movement.

For this purpose, the present invention provides a holder which is preferably stamped or otherwise formed from a single piece of material and includes a disk 13, 60 which has a concentrically arranged sleeve or nipple 14 extending therefrom. This sleeve or nipple is adapted to be inserted through an opening provided along the longitudinal center of the tongue 12 and to be upset or riveted upon the inside of 70 the tongue, as clearly shown in Figure 2 of the drawings.

In addition, the disk 13 has extending therefrom upon the face opposite the sleeve 14, projections 15. These projections are 75 in the form of hollow studs and are rolled from fingers or extensions formed integral with the disk 13.

When in use, one of the projections will be arranged upon each side of the longitudinal center of the tongue and will extend between the crossed portions of the lace 11, while a third projection extends between the crossed portions of the said lace at a point along the longitudinal center 80 of the tongue. Thus, the tongue will be held against sidewise dislodgement, or against movement in a direction toward the toe of the shoe. At the same time, sufficient movement will be permitted to permit the tongue to conform to the movement of the foot of the wearer when walking, the engagement of the lace with the studs 15 automatically centering the tongue after 85 each movement.

In Figures 4 and 5 of the drawings there is illustrated a modified form of the invention. This form is also made from a single piece of sheet metal and comprises a cruciform member 16 having diagonally disposed channels 17 which receive the crossed portions of the lace 11, the walls which form these channels being substantially V-shaped in configuration and extending between the crossed portions of the lace in the manner shown in Figure 4. This form of the invention may be secured to the tongue by any suitable means, such as a rivet 18.

The invention is susceptible of various 110 changes in its form, proportions and minor details of construction and the right is here-

in reserved to make such changes as properly fall within the scope of the appended claim.

Having described the invention what is claimed is:—

A disk for use on the tongue of a shoe having a concentrically arranged sleeve extending therefrom adapted to be inserted

through an opening in the tongue and to be upset or riveted upon the inside of said tongue, said disk also having a plurality of hollow rolled projections formed integrally of the disk and extending in opposed relation to said sleeve.

In testimony whereof I affix my signature.

WILLIAM F. COOK.
